UNITED STATES PATENT OFFICE.

CLYDE S. WRIGHT, OF TOLEDO, OHIO, ASSIGNOR TO THE NATIONAL SUPPLY COMPANY, OF TOLEDO, OHIO, A CORPORATION OF OHIO.

POLISH-ROD CLAMP.

Application filed October 7, 1925. Serial No. 61,150.

To all whom it may concern:

Be it known that I, CLYDE S. WRIGHT, a citizen of the United States, residing at Toledo, in the county of Lucas and State of Ohio, have invented new and useful Improvements in Polish-Rod Clamps, of which the following is a specification.

My invention relates to clamps designed particularly for gripping the polish rods of oil well pumps, but I do not limit the invention to that purpose as it may be used wherever a strong efficient rod clamp is needed.

It is the object of this invention to provide a clamp by which the actuating power is greatly multiplied through the action of a compound lever mechanism operated by a screw or equivalent device.

Referring to the accompanying drawing, Fig. 1 is a side elevation of my clamp showing a rod clamped thereby; Fig. 2, a top view with a portion broken away, and Fig. 3, a plan view with the gates open and a portion broken off.

On the drawing, 1 designates the body member of the clamp. It has between its ends a U-shaped recess 2 having in its back face 3 the groove 4 to receive one side of the polish rod 5. The body has at its ends and substantially in line with the face 3 the trunnions 6 to which mechanism for reciprocating the clamp is attached.

7 is the body gate or clamping member which closes the open side of the U-shaped recess. The gate has a pair of hinge members 8 working in slots 9 in the outer end of the side wall 11 of the recess 2, the hinge members being held in place by the hinge pin 10. The body gate has an inwardly projecting portion 12 which when the gate is closed extends into the recess 2 and has the face 13 lying close to and parallel with the face 3. The face 13 has a groove 14 similar to the groove 4 and lying parallel therewith and directly opposite thereto, so that the two grooves 4 and 14 may engage the opposite sides of the polish rod 5 or other bar or rod. When the gate is closed, a lug 15 on the face 13 is in the recess 16 in the face 3, the lower face of the lug resting on the bottom of the recess to support the outer end of the gate and relieve the hinge pin and hinge members of any shearing action.

The remaining end wall of the recess 2 has the ears 17 between which the hinge

membebrs 18 on one end of the lever or clamp-
ing gate 19 is pivoted by means of the hinge
pin 20. The inner face of the lever 19 has
close to its pivotal portion the shoulder or
lug 21 arranged to engage the shoulder 27 on
the free end of the body gate when the lat-
ter is closed and to force the body gate in-
wardly as the lever is swung to its closed po-
sition overlying the body gate.

The side wall 11 has between the recesses
9 the recess 22 to receive the eye bolt 23
through whose eye the hinge pin 10 extends.
The eye bolt swings on the pin 10 and has
the clamping nut 24 threaded thereon. The
free end of the lever 19 has the open slot 25
into which the bolt may be swung when the
lever 19 is in operative position as shown in
Fig. 1. When the bolt is in the slot the nut
24 may be screwed down by the aid of the
hand lever 26 against the back of the lever
19 to cause the latter by means of the shoul-
der 21 to force the body member inwardly
so as to grip the rod 5 firmly in the grooves
4 and 14.

It is seen that the power delivered by the
nut 24 to the lever 19 is greatly multiplied
since the length of the lever 19 is many times
the distance of the shoulder 21 from the cen-
ter of the pivot pin 20, and since the distance
between the center of the pin 10 and the
point of application of the shoulder 21 to
the body gate 7 is greater than the distance
from the center of the pin 10 to the center of
the rod 5.

I claim—

1. A body member having a rod-engaging
surface, a body gate member hinged at one
end to the body member at one side of said
surface, a clamping gate hinged at one end
to the body member at the opposite side of
the said surface and having a portion close
to its pivot to engage the free end of the
body gate member and force the latter to-
ward the body member and into gripping
contact with a rod engaging the said surface,
and power means carried by one of the said
members and applicable to the free end of
the clamping gate member to increase the
pressure of the said portion against the body
gate.

2. A body member having a rod-engaging
surface, a body gate hinged at one end to
the body member at one side of said surface,
a clamping gate hinged at one end to the

body member at the opposite side of the said surface and having a portion close to its pivot to engage the free end of the body gate and force the latter toward the body member and into gripping contact with a rod engaging the said surface, a threaded bolt having an eye pivoted on the pivot of the body gate, and a nut on the bolt for operating the clamping gate to increase the pressure of the said portion against the body gate.

In testimony whereof, I hereunto affix my signature.

CLYDE S. WRIGHT.
